Primary Examiner — Katie Jane Stofko(74) *Attorney, Agent, or Firm* — Merchant & Gould P.C.(57) **CLAIM**

The ornamental design for a wrapped pet treat, as shown and described.

DESCRIPTION

FIG. 1 is a top, front perspective view of a wrapped pet treat according to the new design, the portions shown in broken lines forming no part of the claimed design.

FIG. 2 is a right side elevation view of the embodiment of FIG. 1;

FIG. 3 is a left side elevation view of the embodiment of FIG. 1;

FIG. 4 is a front elevation view of the embodiment of FIG. 1;

FIG. 5 is a back elevation view of the embodiment of FIG. 1;

FIG. 6 is a top plan view of the embodiment of FIG. 1;

FIG. 7 is a bottom plan view of the embodiment of FIG. 1; and,

FIG. 8 is a bottom, back perspective view of the embodiment of FIG. 1.

The lines shading and the stippled shading showing in FIGS. 1-8 represent a contrasting appearance.
